(57) **CLAIM**

I claim the ornamental design for a laser tag shooting device, as shown and described.

DESCRIPTION

FIG. 1 is a top, perspective view of a first embodiment of a laser tag shooting device of my new design.

FIG. 2 is a bottom, perspective view of a laser tag shooting device of FIG. 1.

FIG. 3 is a side elevation view of the left side of a laser tag shooting device of FIG. 1.

FIG. 4 is a side elevation view of the right side of a laser tag shooting device of FIG. 1.

FIG. 5 is a front elevation view of a laser tag shooting device of FIG. 1.

FIG. 6 is a rear elevation view of a laser tag shooting device of FIG. 1.

FIG. 7 is a top plan view of a laser tag shooting device of FIG. 1.

FIG. 8 is a bottom plan view of a laser tag shooting device of FIG. 1.

FIG. 9 is a top, perspective view of a second embodiment of a laser tag shooting device of my new design.

FIG. 10 is a bottom, perspective view of a laser tag shooting device of FIG. 9.

FIG. 11 is a side elevation view of the left side of a laser tag shooting device of FIG. 9.

FIG. 12 is a side elevation view of the right side of a laser tag shooting device of FIG. 9.

FIG. 13 is a front elevation view of a laser tag shooting device of FIG. 9.

FIG. 14 is a rear elevation view of a laser tag shooting device of FIG. 9.

FIG. 15 is a top plan view of a laser tag shooting device of FIG. 9; and,

FIG. 16 is a bottom plan view of a laser tag shooting device of FIG. 9.

In the drawings, the broken lines depict portions of a laser tag shooting device that form no part of the claimed design. The laser tag shooting device includes a symbolic break

(Continued)

along its length drawn in broken lines. The break lines and the area between the break lines forms no part of the claimed design.

1 Claim, 12 Drawing Sheets
